AUTOMATIC DIVIDING DEVICE FOR
CONVEYER SYSTEMS

William H. Hartmann, Lemay, Mo.

Application April 3, 1951, Serial No. 218,967

9 Claims. (Cl. 198—31)

1

The present invention relates to an improved device for use with conveyor systems of the type extensively employed in bottling, canning, and similar industries.

The invention is primarily designed for incorporation in that type of conveyor system wherein it is requisite that a single line of bottles, cans or the like, traveling from one station be divided into two separate lines each leading to another station.

Granted to me on July 18, 1950, were Letters Patent No. 2,515,871 covering an automatic dividing device for attaining such objectives. However, the device disclosed in said patent necessarily requires the presence of an air pressure system in the plant, since the operating mechanism includes a rotary valve and a pair of diaphragms actuated by compressed air.

Most of the larger plants are equipped with a compressed air system, and under those circumstances, my patented device has been found to achieve its objects in a most efficient manner.

However, many of the smaller plants are not equipped with a compressed air system, so that installation of my said device would also entail the prohibitive expense of installing such a system. On the other hand, these small plants do have electric power available, as is understood.

The primary object of the present invention therefore, is to provide an automatic dividing device which may be easily installed in the conveyor system of a bottling plant or the like; which requires only the availability of an electrical socket or other outlet for successful operation; which is simple in design; positive in action; and which will attain the same objectives as the device disclosed in said patent.

Specific features and advantages not referred to above, will be noted in the description to follow, reference being had also to the accompanying drawings, wherein the preferred embodiment of my invention is illustrated.

In said drawings:

Fig. 1 is a diagrammatical illustration in top plan of a conveyor system wherein is incorporated the automatic dividing device comprising the present invention;

Fig. 2 is a side elevational view of Fig. 1, with guide rail elements omitted;

Fig. 3 is a top plan view of the dividing device, shown per se;

Fig. 4 is a side elevational view thereof;

Fig. 5 is a fragmentary elevational view of the device as it appears from the side opposite that portrayed in Fig. 4;

Fig. 6 is a top plan view of the device with

2

a top cover plate removed, and the non-stationary mechanism shown in one position;

Fig. 7 is a similar view, with said mechanism shown in an alternate position;

Fig. 8 is an approximately central sectional view of the device with certain elements portrayed in elevation;

Fig. 9 is a fragmentary horizontal sectional view taken approximately on line 9—9 in Fig. 4;

Fig. 10 is a vertical transverse sectional view taken on line 10—10 in Fig. 6;

Fig. 11 is a side elevational view of one of a pair of deflector plates associated with the invention;

Fig. 12 is an end view of said deflector plate, a slide lug being shown secured thereto in broken lines;

Fig. 13 is a bottom plan view of a micro-switch control assembly per se;

Fig. 14 is a schematic layout of the electrical connections.

With particular reference to Figs. 1 and 2, numeral 20 designates a standard endless conveyor, only the delivery or discharge end of which is portrayed. The conveyor travels in the direction indicated by the arrows *a*, and may be driven by power applied to shaft 24, or otherwise, as is understood.

For explanatory purposes, it will be assumed that conveyor 20 is part of a system for conveying bottles in a single line from one station of a bottling plant to a division point, where the single line is divided into two separate lines each leading to another station.

It is to be understood however, that the invention is not restricted to bottle conveyor systems, but that it may be employed with equal efficiency in other analogous conveyor apparatus.

That is to say, the bottle conveyor system illustrated in exemplary only, and the invention could be incorporated in any conveyor system wherein it is desired to divide a single line of articles traveling on one conveyor, into two separate lines each traveling on another conveyor.

Reverting now to Figs. 1 and 2, bottles propelled forwardly in upright position on conveyor 20, are indicated by broken lines and designated B. Said bottles may be spaced as shown; or otherwise, it being noted that the instant device is so designed that its operation is not dependent upon spacing. In other words, the device will operate regardless of whether the articles on conveyor 20 are evenly or unevenly spaced; or whether they are in physical contact with one another.

Overlapping the discharge end of said con-

veyor, and adjacent either side thereof, is another endless conveyor which travels in the same direction, and the upper stretch of which is in the same plane, as that of conveyor 50.

The first of these conveyors is designated 26, and leads to one station, the second is designated 28 and leads to another station.

Along either marginal edge thereof, conveyor 20 is provided with stationary ware guide rails 32, shown only diagrammatically in Fig. 1.

The conveyors 26 and 28 respectively, also have similar guide rails 34 and 36 along their marginal edges, the inner rails in both instances forming a continuation of guide rails provided on the dividing device, as will appear.

An angularly disposed guide rail 38 connects one of said guide rails 32 with the outer rail 34, and a similar rail 40 connects the other rail 32 with outer rail 36.

All of these guide rails are so spaced as to prevent the bottles from tipping as they travel on the conveyors, and during the time they are being transferred from the single line conveyor 20 to either of the conveyors 26 or 28, as is understood.

It is noted that the guide rails form no part of the instant invention, any appropriate rail construction of this nature being suitable.

Removably mounted on a standard 42 as shown, or on any other suitable stationary support adjacent the overlapping conveyor end portions, is the divider unit comprising the present invention. It is generally designated by reference numeral 44.

Included in this device is a substantially rectangular housing or casing having a bottom wall 46, side walls 48, a rear end wall 50, and a forward wall 52.

As seen to best advantage in Fig. 9, said forward wall includes converging portions 54 merging at their forward ends into a substantially triangular body portion 56, and at their rear ends into the side walls 48.

Exteriorly, each converging wall portion 54 is recessed as at 58 to provide a smooth vertical surface or slideway for a purpose to appear.

Secured to each side wall 50, as by countersunk screws 60 or the like, are upper and lower guide rail members 62 and 64 respectively. The cross-sectional configuration of these guides, as best seen in Fig. 10, is preferably semi-circular. As hereinbefore noted, and as portrayed in Fig. 1, the rails 62 and 64 are alined with inner rails 34 and 36, when the divider is properly installed.

At their forward ends, the rail members 62 and 64 are bevelled off as at 66, so as to merge into the outermost face portions 68 of the converging walls 54. In other words, as the drawings clearly illustrate, rails 62 and 64 combine with face portions 68 to produce smooth, continuous guides for the ware during the transfer operation as will be seen.

Further, the forward ends of said rail members are cut away or recessed at 70, so as to provide clearance for a pair of ware deflecting plates which, as will appear, are adapted to be alternately reciprocated horizontally along the surfaces 58.

With particular reference to Fig. 9, each wall 54 is provided with an elongated horizontal slot 72, through each of which projects a lug 74, slideable therein. Exteriorty of the housing, a deflector plate 76 is secured by a countersunk

screw 78 to one lug, and a deflector plate 80 is similarly secured to the other lug, as shown.

In Figs. 11 and 12, the deflector plate 80 is shown detached. It includes a body portion 82, an integral forwardly projecting upper finger 84, a similar lower finger 86, and a similar intermediate finger 88. The extremities of said fingers are rounded as at 90, so that as will appear, should the bottles of the single line be in contact with one another, insertion between the leading unit and the next adjacent unit is facilitated.

The top and bottom edges of plate 80 are recessed at 92 so as to provide tongue portions 94 slidably mounted in longitudinal grooves 96 formed in the exterior face portions 68 of one converging wall 54.

The plate 76 is similar to plate 80, and appears to best advantage in Fig. 5, where it is seen to include a body portion 98, provided with tongue portions 100 along its top and bottom edges. Similar to those of plate 80, these tongue portions are slidably mounted in longitudinal grooves 96 formed in the exterior face portions 68 of the other converging wall 54.

Integral with the body portion of plate 76, are a pair of forwardly projecting fingers 102, so spaced relative to the spacing of fingers 84, 85 and 86, that the latter may freely traverse the former, and vice versa, when the plates 76 and 80 are reciprocated. The extremities of fingers 102 are also rounded as at 104.

The means for alternately reciprocating the deflector plates will now be described, with particular reference to Figs. 6 and 7.

Each of the lugs 74 is provided with a vertical threaded aperture 106 for the reception of a pivot screw.

Numeral 108 designates a first link, the forward end of which is pivotally connected by screw 110 to that lug which is secured to deflector plate 76, and the rear end of which is pivotally connected to a rotary disc 112 by a screw 114.

Numeral 116 designates a second link, the forward end of which is pivotally connected by a screw 118 to that lug which is secured to deflector plate 80, and the rear end of which is pivotally connected to said rotary disc by a pivot screw 120. With this arrangement, it should be obvious that counter-clockwise rotary motion of disc 112 will cause deflector plate 76 to slide forwardly from the position it occupies in Fig. 6, to its Fig. 7 position. Simultaneously, deflector plate 80 will slide rearwardly from the position it occupies in Fig. 6, to its Fig. 7 position.

As seen particularly in Fig. 8, disc 12 has a depending hub portion 124, and is rotatably mounted on a stud 126, the reduced threaded lower end of which is in engagement with the bottom wall 46.

Intermittent partial rotation of the disc 112 is effected by the alternate energization of a pair of solenoids 128 and 130, each of which is appropriately mounted within the casing on a bracket 65 secured to the bottom wall 46, as shown. The solenoids are conventional, and each includes a movable armature 132 which is pulled in when the solenoid is energized, and is free to be moved outwardly when the solenoid is de-energized, as is understood.

Outward movements of the armatures are limited by enlarged head members 134 thereon, and a rectangular opening 136 is provided in the adjacent side wall 50 to accommodate said members, as best shown in Fig. 6.

Numerical 138 designates a horizontally disposed lever, pivotally mounted on a stud 140 as clearly shown in Fig. 10. The rear end of lever 138 has a pivotal connection 142 with a first short link 144, and the latter in turn, has a pivotal connection 146 with the projecting end of the armature 132 associated with solenoid 130.

The forward end of said lever has an elongated slot 148 therein, through which passes a screw 150 into engagement with a threaded aperture provided in disc 112. An intermediate portion of lever 138 has a pivotal connection 152 with a second short link 153, and the latter in turn has a pivotal connection 154 with the projecting end of the armature 132 associated with solenoid 128. A rectangular opening 156 is provided in the adjacent side wall 50 to accommodate these parts.

From the foregoing, and an inspection of Figs. 6 and 7, it should be apparent that energization of solenoid 128 will rotate disc 112 counter-clockwise from its Fig. 6 to its Fig. 7 position, and that energization of solenoid 130 will rotate said disc clockwise from its Fig. 7 to its Fig. 6 position.

A demountable cover plate 158 is provided for the device, being maintained in position above the casing by spacer elements 160, and screws 162, as illustrated.

Permanently supported on said cover by means of an angular bracket 164, is a conventional micro-switch assembly designated 166. As best seen in Fig. 8, the actuating plunger 168 of said switch projects downwardly and freely through an opening 170 in said cover plate.

As schematically shown in Fig. 14, plunger 168 is normally biased to its lowermost position by means of a spring 172 incorporated in the micro-switch assembly, as is understood. In such position, a circuit for energizing solenoid 128 is established via line 174, movable blade 176, stationary contact 178, lead 180, said solenoid, and line 182.

This circuit is broken however when plunger 168 is raised. Simultaneously a circuit for energizing solenoid 130 is thus established via line 174, movable blade 176, stationary contact 184, lead 186, said solenoid, lead 188, solenoid 128, and line 182.

As shown only in Fig. 1, a conventional plug 190 may be attached to the free ends of lines 174 and 182, as is understood. It is also noted, that a manual On and Off switch may be incorporated in the wiring if desired.

In Fig. 13 there is shown in bottom plan, an assembly for controlling the movements of the micro-switch plunger. Referring also to Figs. 7 and 8, said assembly includes an arm 192 pivotally mounted at its forward end by means of a screw 194 which engages in a threaded aperture 196 provided in the triangular body portion 56 of casing wall 52. A washer 198 about said screw, is interposed between the bottom face of said arm and the upper surface of the casing, so that the rearwardly extending portion of the arm is free to oscillate about pivot 194.

Adjustably secured to the free extremity of arm 192, as by a slot and screw connection 199, is an arcuate stop member 200 which limits the oscillatory travel of said arm. Stop member 200 appears in end elevation in Fig. 10, where it is seen that each terminal end thereof is adapted to strike against one of the walls 50 as the arm 192 oscillates, as will appear.

Numerical 202 indicates an element having a slightly rounded top surface which occupies a plane above the upper face of arm 192, and suf-

ficiently above the plane normally occupied by the lower extremity of plunger 168.

As illustrated in the drawings, element 202 is in the form of a rivet, and is disposed to one side of the longitudinal centerline of arm 192 so that, when said arm is in its Fig. 6 position, rivet 202 will force plunger 168 upwardly, to thereby close the circuit which energizes solenoid 130.

However, when arm 192 is in its Fig. 7 position, rivet 202 is not in contact with said plunger so that the downwardly biasing means incorporated in the micro-switch closes the circuit which energizes solenoid 128, as has been explained.

One of the principal features of the invention is that each successive leading unit of the single line of bottles will swing arm 192 in a direction opposite to that effected by its predecessor.

To attain this end, a pair of rollers 204 and 206 are adjustably mounted by means of a support 208, to said arm as at 210. Each of said rollers is freely rotatable about a vertical pin which includes a peened top portion 212, and a similar but preferably larger bottom portion 214, as the drawings disclose.

With this arrangement, it should be manifest that the rounded portions 214 not only support arm 192 intermediate its pivotal mounting and the free end thereof, but also facilitate the oscillations thereof.

Operation

Although the operation should be clear from the foregoing description and reference to the drawings, a brief résumé thereof will now be presented.

Assuming that a single line of bottles B on conveyor 20 is approaching device 44, and that deflector plate 80 is in the position illustrated in Figs. 1 through 6, the leading bottle will be diverted toward conveyor 26 by the rounded extremities of fingers 84, 86 and 88.

At this time, rivet 202 is forcing plunger 168 upwardly, so that solenoid 130 is being energized whereby to maintain deflector plate 76 in a retracted position, and simultaneously to maintain deflector plate 80 in an extended position.

In such extended position, the rounded extremities 90 of fingers 84, 86 and 88 project across the longitudinal centerline of conveyor 20, so that the leading bottle B is deflected toward conveyor 26 as indicated by arrow b in Fig. 6.

As said bottle continues to advance as indicated by arrow c, it bears against projecting roller 206 to swing arm 192 to its Fig. 7 position, whereby as should now be manifest, deflector plate 76 slides forwardly simultaneously with the withdrawal of plate 80.

As a result, the rounded extremities 104 of fingers 102 project across the longitudinal centerline of conveyor 20, so that the succeeding leading bottle B is deflected toward conveyor 26 as indicated by arrow d.

As said bottle continues to advance, it bears against projecting roller 204 to swing arm 192 to its Fig. 6 position for a repetition of the cycle. From the foregoing it should be evident that my invention provides an electrically operable device for automatically dividing a single row of bottles or similar articles into two separate rows. It should likewise be evident that the invention may be incorporated in standard conveyor systems without requiring structural changes in them.

Obviously, the device may be modified without departing from the principles of the invention.

It is to be understood therefore, that the inven-

tion is not to be limited to the precise details illustrated and described.

What I claim is:

1. A device for automatically dividing a single line of ware or the like on one conveyor into two separate lines on a pair of adjacent conveyors, said device including a pair of deflector plates reciprocable intermittently across the path of the leading unit in said single line; a micro-switch assembly including a depending plunger the position of which is intermittently reversed by successive leading units of said single line; bracket means for mounting said switch assembly; a pair of solenoids alternately energizable by said micro-switch for actuating the movable armatures of said solenoids; and means operable by said armatures for intermittently reciprocating the deflector plates aforesaid.

2. The device of claim 1, wherein each of the intermittently reciprocable deflector plates is provided with an upper and a lower marginal tongue portion in slidable engagement respectively with a complementary groove portion of an upper and a lower exterior face portion formed on a casing incorporating said device, and wherein in each deflector plate includes a plurality of integral spaced projecting finger members adapted to be intermittently reciprocated across the longitudinal centerline of said first conveyor, and across one another.

3. The device of claim 1 wherein the pair of deflector plates includes a first plate and a second plate, said first plate comprising a substantially rectangular body portion recessed along its top and bottom marginal edges to provide tongue portions; a countersunk aperture in said body portion; an upper, a lower, and an intermediate finger member integral with the body portion and projecting forwardly therefrom, the extremities of said fingers being rounded; said second plate comprising a substantially rectangular body portion recessed along its top and bottom marginal edges to provide tongue portions; a countersunk aperture in said body portion; a pair of finger members integral with the body portion and projecting forwardly therefrom, said fingers being so located as to pass freely through the spaces obtaining between the fingers of said first plate, and the extremities thereof being rounded; the countersunk aperture of each plate being adapted to receive the head portion of a screw the threaded shank portion of which is in engagement with a lug member slidably operable in an elongated horizontal slot formed in one wall of a casing included in the device.

4. The device of claim 1, wherein the means operable by said armatures for intermittently reciprocating the deflector plates includes a horizontally disposed lever pivotally mounted on a vertical stud rigidly secured to the bottom wall of a casing incorporating said device; a first short link having a pivotal connection at one end with the rear end of said lever and at its other end with the armature of one of said solenoids; a second short link having a pivotal connection at one end with an intermediate portion of said lever and at its other end with the armature of the other of said solenoids; a rotatable disc mounted on a vertical stud rigidly secured to the bottom wall of said casing; an elongated slot in the forward end of said lever; a pivot screw passing through said slot and into engagement with a threaded aperture provided in said disc; and a pair of links each pivotally connected

at one end to said disc and at its other end to a slidably mounted lug secured to one of said deflector plates.

5. In a divider of the character described: a micro-switch having a depending downwardly biased actuating plunger; a first and a second solenoid; and means whereby intermittent energization of said solenoids is effected by a unit of ware, said means comprising a horizontally disposed arm, a pivotal mounting for one end thereof; a stop member adjustably secured to the other end thereof; a rivet secured to said arm the upper surface of which is in a plane above the plane normally occupied by the lowermost portion of said plunger; and a pair of rollers rigidly supported by said arm and adapted to be alternately engaged by successive leading units of ware for oscillating said arm to intermittently effect the energization of said first and second solenoids.

6. A divider unit for incorporation in a conveyor system of the type described, said unit including: a substantially rectangular casing having a bottom wall, side walls, a rear end wall, and a convergent forward wall terminating in a rounded apex portion; a pair of solenoids appropriately supported within said casing in spaced relation to the bottom wall thereof, each solenoid including a movable armature; a pair of intermittently reciprocable deflector plates slidably mounted on said casing; a demountable cover plate for the casing and spacer means for sustaining same in a plane above the top of the casing; a micro-switch assembly mounted on said cover plate; a pivotally mounted oscillatory assembly for alternately opening and closing a pair of electrical circuits associated with said switch and said solenoids; and means connected with the armatures of said solenoids for reciprocating said deflector plates.

7. A divider unit for incorporation in a conveyor system of the type described, said unit including: a substantially rectangular casing having a bottom wall, side walls, a rear end wall, and a convergent forward wall terminating in an exteriorly rounded substantially triangular apex body portion; a demountable cover plate for the casing maintained in vertically spaced relation thereabove; a micro-switch assembly including a depending actuating plunger rigidly mounted on said cover plate; an opening formed in said plate through which said plunger extends; an oscillatory assembly pivotally mounted on said apex body portion between the casing and the cover plate for controlling the vertical movements of said actuating plunger; a pair of rollers included in said assembly adapted to be engaged by successive articles being propelled along the first conveyor included in said system for intermittently oscillating the same; a pair of solenoids responsive to the said micro-switch; a pair of slidably mounted deflector plates; and means operable by said solenoids for intermittently reciprocating said deflector plates across the first conveyor aforesaid.

8. In combination with a conveyor system of the character described, a device operable by successive containers to divide a single line into two separate lines of containers, said device including a pair of angularly disposed deflector plates reciprocable across the path of the single line; linkage controlled by a rotary disc for intermittently reciprocating said plates; a pivotally mounted horizontally disposed lever for oscillating said disc under the action of a pair of

solenoids; a micro-switch assembly; and means for actuating said switch assembly to alternately energize one, then the other of said pair of solenoids.

9. In a device of the character described, a pair of solenoids for intermittently reciprocating a pair of slidably mounted deflector plates, each solenoid including a movable armature having a pivotal link connection with a pivotally mounted horizontally disposed lever secured at one end by an elongated slot and screw connection to a

5 10

rotary disc; a pair of links each pivotally connected at one end to said disc and at its opposite end to a lug rigid with one of said plates and slidably in an elongated slot provided in the casing incorporating said device; a micro-switch; and means for controlling said switch to intermittently energize said solenoids.

WILLIAM H. HARTMANN.
